G. F. MATTESON

ROLLER CARRIAGE

Filed May 11, 1923

Inventor
George F. Matteson

By Eliza B. Ford Attorney

UNITED STATES PATENT OFFICE.

GEORGE FRANKLYN MATTESON, OF ROCKY HILL, CONNECTICUT, ASSIGNOR, BY MESNE ASSIGNMENTS, TO THOMSON-NATIONAL PRESS COMPANY, INC., OF LONG ISLAND CITY, NEW YORK, A CORPORATION OF DELAWARE.

ROLLER CARRIAGE.

Application filed May 11, 1923. Serial No. 638,349.

To all whom it may concern:

Be it known that I, GEORGE FRANKLYN MATTESON, a citizen of the United States, residing at Rocky Hill, in the county of Hartford and State of Connecticut, have invented certain new and useful Improvements in Roller Carriages, of which the following is a specification.

My said invention relates to a roller trip mechanism for printing presses and it is an object of the same to provide a device of the character described with improved latching means for holding one or more inking rollers out of form-engaging position, said latching means being positively operated to release the form rollers for contact with the ink cylinder and being also positively released at the lower end of their travel by means traveling at substantially the same speed as the roller carriage, thus doing away with the destructive action occurring in certain known types of trip mechanism due to the shock caused by the striking of a latch or connected part on the roller carriage against a rigid abutment on the fixed frame of the press. As is known mechanisms of this type freshly inked rollers are applied to the bottom of the form on the upward stroke of the roller carriage thus effecting a double rolling of the form at each revolution of the press but the latch operating devices travel with the roller carriage and substantially at the same speed as the latch or latches.

Another object of the invention is to provide a simple and effective operating means for releasing a plurality of latches where it is desirable to hold out a plurality of form rollers at some stage of the operation.

Another object of the invention is to provide a latch of improved shape for cooperating with an abutment on the journal box of a form roller for holding it away from the form.

Still another object of the invention is to provide improved means to insure the release of the form rollers from their outermost inoperative position before they reach a position of interference with the form grippers and platen.

Referring to the accompanying drawings, which are made a part hereof and on which

similar reference characters indicate similar parts,

Figure 1 is an elevation of part of a printing press with my improved device attached thereto, and

Figure 2 is a similar view on an enlarged scale.

In the drawings reference character 10 indicates a part of the main frame of the press having a groove 11 for guiding pins or rollers 12 on the form roller carriage. Rigid with the part having said guide groove or fixed in position closely adjacent thereto are a plurality of cams 13, 14 and 15 adapted to contact with truck wheels at the ends of form rollers indicated at 16 and 17. The form rollers are rotatably mounted in journal bearings 18 and these journal bearings have laterally projecting stems 19 slidably mounted in horizontal openings in a side member 20 of the carriage. Springs 21 surround the stems 19 and bear at one end against a flange of the member 20 and at the other end against abutments 22 on the stems, which abutments are here indicated as consisting of washers held in place by cotter pins 23.

A pair of screws 24 project laterally from the side of the roller carriage and a bar 25 is held in place by the screws, slots being provided at 26 in said bar to permit the same to move relatively to the carriage. Each of the journal bearings for the form rollers is provided with an inclined cam face at 27 and the bar has correspondingly inclined surfaces at 28 whereby when the bar is moved downward relatively to the carriage the opposed inclined faces of each pair will slide over another and force the

journal bearings with the form rollers to the left in the drawings against the tension of springs 21 after which the flat vertical faces of the bar adjacent to said inclined faces will slide down alongside the flat vertical faces of the journal bearings and hold the form rollers in extreme outer or inoperative position. For convenience in operating the slide to bring the rollers into said outer position or to release them therefrom, the carriage is provided with a manually operable lever 29 pivoted at 30 and having a ball at 31 engaging a socket in the sliding bar.

100

A rockarm 32 on a rockshaft indicated at 33 in dotted lines is provided as usual for moving the roller carriage up and down, it being connected thereto by a link 33 pivoted to the carriage at 34 which also functions as a lever to release the latches on the carriage. A nose 35 on the lever is adapted to engage an abutment at the lower right hand corner of a latch 36 in the form of a pawl pivotally mounted on the roller carriage and notched at its forward end to provide a vertical face adapted to engage with a projecting abutment 37 in the form of a pin on the lowermost journal box. A lateral arm 38 on the lever 33 is bent upward at its outer end and adapted to strike the lower end of the slide 25 and push the slide up to disengage it from the journal boxes before the roller carriage has traveled far enough to strike against the frame grippers or the platen of the press, the springs 21 then acting to return the rollers 17 to form-engaging position and the rollers 16 to the intermediate position where they are temporarily held by the latches herein described.

In some cases it is desirable to provide more than one of the form rollers with means for holding it away from the face of the type on the downward stroke of the carriage and for this purpose I have provided an additional latch 39 also pivotally mounted on the carriage and generally similar to the latch 36 but provided with a downward projection 40 in place of the operating means for the latch 36. It will be evident that when the latch 36 is raised, the latch 39 will also be raised out of engagement with its pin 37.

In the operation of my device it will be seen that when the roller carriage is in its uppermost position as shown, the hand lever 29 may be operated to move the sliding bar 25 downward and so force the form rollers into their outer inoperative position where they will be held until the bar is moved upward to release them. This may ordinarily be done by the operative before starting the press but should he forget or neglect to do so then as the link 33 draws the carriage down the upper end of arm 38 will swing about the pivot 34 so as to raise the slide and release the rollers to the action of the springs before reaching a position to cause damage.

As the carriage approaches its lowermost position the wheels of the lower pair of rollers 16 will ride up over cams 13 and 14 respectively, but out of contact with the cams since the rollers are held in their outer position by latches 36 and 39. Rockarm 32 is now at its lowermost position, the link 33 and carriage 25 having been moved down by it into a position where the link 33 stands at substantially the same angle to the carriage as in the uppermost position

of said parts. In this position the nose 35 strikes against the latch 36 and lifts it out of engagement with the projection 37, this latch in turn lifting the upper latch 39 by means of its lug 40. When the latches are thus lifted out of the position indicated in Figure 2 the springs 21 move the journal bearings and therefore the lower pair of form rollers toward the right. If the cams 13 and 14 were absent the wheels of the form rollers would strike noisily on their tracks, but with the construction shown they impinge first on the high points of the cams, already close to the wheels and then ride gently down the cam faces to the tracks, when the freshly inked rollers apply the ink beginning at the lower end of the form as specified. As the carriage approaches its upper position the wheels of the form rollers ride over the cam 15 and force the journal bearings of the lower pair of rollers to the left into a position where they would be engaged by the latches but for the fact that the link 33 by means of its nose 35 lifts the latches into the position indicated in Figure 1 so that all the rollers are in position to engage with the ink cylinders 41 and 42 respectively as the carriage travels at low speed toward its upper position. When the carriage again starts down the truck wheels roll over the cam 15 and as the nose 35 is now at or near the position of Figure 2 the latches again engage behind the pins 37 thereby holding the lower pair of form rollers out of form-engaging position so that the upper part of the form is inked by the upper pair of rollers while the lower pair of rollers is adapted to act with full effect on the lower end of the form during the reverse stroke of the carriage in a manner well understood in the art.

It will be obvious to those skilled in the art that the details of my invention may be modified in various ways without departing from the spirit of the invention, and therefore I do not limit myself to the specific embodiment shown in the drawings and described in the specification but only as indicated in the appended claims.

Having thus fully described my said invention, what I claim as new and desire to secure by Letters Patent, is:

1. A printing press comprising a reciprocating carriage, form rollers thereon movable toward and from form-engaging position, one or more pivoted latches on the carriage adapted to hold certain of said form rollers out of form-engaging position, and means movable with the carriage adapted to move said latches about their pivots near opposite ends of the travel of the carriage, substantially as set forth.

2. A printing press comprising a reciprocating carriage, form rollers thereon movable toward and from form-engaging posi-

tion, journal bearings movable with said rollers, an abutment on one of said journal bearings, a pivoted latch on the carriage adapted to engage the abutment and hold 5 the corresponding roller out of form-engaging position, a link connected to the carriage for reciprocating the same, and a nose on said link for lifting said latch, substantially as set forth.

10 3. A printing press comprising a reciprocating carriage, form rollers thereon movable toward and from form-engaging position, journal bearings movable with said rollers, a pivoted latch on the carriage for holding one of said form rollers out of form-engaging position, a link secured to the carriage for reciprocating the same, said link having means for releasing said latch, a second pivoted latch arranged to hold another roller out of form-engaging position, and connections from the first latch to the second for releasing the second latch, substantially as set forth.

15 4. A printing press comprising a reciprocating carriage, form rollers thereon movable toward and from form-engaging position, means for manually moving all of said rollers into an inoperative position on the carriage, said means being always in operative relation to the rollers, independent means for holding one or more rollers out of form-engaging position during a stroke of the carriage in one direction, means for reciprocating the carriage including a link 20 and means on the link for releasing all of said rollers automatically, substantially as set forth.

25 5. A printing press comprising a reciprocating carriage, form rollers thereon movable toward and from form-engaging position, journal bearings for said form rollers, a slidable bar on the carriage having cam faces engageable with cam faces on each of said journal bearings to move all the 30 form rollers out of operative position and vertical faces engageable with the side faces of the journal bearings for locking the rollers out of operative position, manual means for moving said bar in a direction to render 35 the rollers inoperative, and automatic means for returning said bar during the downward movement of the carriage before it reaches a point of interference with the platen, substantially as set forth.

40 6. A printing press comprising a reciprocating carriage, form rollers thereon movable toward and from form-engaging position, journal bearings for said form rollers, a movable bar on the carriage having cam faces engageable with cam faces on the journal bearings to move the form rollers into operative position, vertical faces engageable with the side faces of the journal bearings 45 for locking the rollers in inoperative position, manual means for moving said bar

in a direction to render the rollers inoperative, automatic means for returning said bar during the downward movement of the carriage before it reaches a point of interference with the platen, means at the upper 50 end of the carriage travel for moving one or more of said rollers into a second inoperative position, latches for holding them in the last named position, a link for reciprocating the carriage, means on the link 55 for disengaging the latches at the upper end of the carriage travel, and means also on the link for moving the slidable bar in a direction to release the rollers, substantially as set forth.

60 7. A printing press comprising a carriage, means for reciprocating the carriage, form rollers on the carriage, means for inking said rollers, means for moving all of said rollers out of operative position with relation to said inking means, independent means for holding certain of said rollers out of engagement with the printing surface during the outward stroke of the carriage, and means to release said holding means at 65 the end of such stroke, substantially as set forth.

70 8. A printing press comprising a carriage, means for reciprocating the carriage, form rollers on the carriage, means for inking 75 said rollers, a longitudinally reciprocating bar movable in one direction for rendering all the rollers inoperative, and means traveling with the carriage arranged to move the bar in the opposite direction to release the 80 rollers by a movement approximately in the direction of the length of the bar, substantially as set forth.

75 9. A printing press comprising a carriage, means for reciprocating the carriage, form 85 rollers on the carriage, means for inking said rollers, means for holding all of said rollers out of operative position with relation to said inking means, independent means for holding certain of said rollers 90 out of engagement with the printing surface during the outward stroke of the carriage, and means traveling with said carriage for releasing both said holding means, substantially as set forth.

100 10. A printing press comprising a carriage, means for reciprocating the carriage, including a link attached thereto, form rollers on the carriage, means for inking said rollers, a bar slidable up and down on the 105 carriage adapted in one position to hold the rollers out of operative position, latches adapted to hold certain of said rollers out of operative position, an abutment on the link to move said bar into inoperative position 110 during outward stroke of the carriage, and another abutment to release the latches during the reverse stroke thereof, substantially as set forth.

11. A printing press comprising a recip-

recating carriage, form rollers thereon, at my hand and seal at Rocky Hill, Connecticut, on the 7th day of May, A. D. nineteen hundred and twenty-three.

5 the carriage for reciprocating said carriage, and means on the link for releasing such latch prior to the return stroke, substantially as set forth.

In witness whereof, I have hereunto set

GEORGE FRANKLYN MATTESON. [L.S.]
